COMBINED TAPE RECORDER AND RADIO RECEIVER

Harry K. Matsuda, Chicago, Ill., assignor to Ampex
Corporation, Redwood City, Calif., a corporation
of California

Filed June 13, 1966, Ser. No. 2,667

Term of patent 14 years

(Cl. D26—14)

FIGURE 1 is a front, top and left side perspective view of a combined tape recorder and radio receiver with the front cover panels open, showing my new design;

FIGURE 2 is a rear, top and right side perspective view; and

FIGURE 3 is a front, top and left side perspective view with the front cover panels closed, the bottom being identical in appearance to the top.

I claim:

The ornamental design for a combined tape recorder and radio receiver, substantially as shown and described.
